UNITED STATES PATENT OFFICE.

HERMAN C. HEATON, OF CHICAGO, ILLINOIS, ASSIGNOR TO YARNALL-WARING COMPANY, OF PHILADELPHIA, PENNSYLVANIA, A CORPORATION OF PENNSYLVANIA.

METERING BOILER.

Application filed November 17, 1924. Serial No. 750,330.

My invention relates to water meters for metering feed water to boilers and more particularly to V-notch weirs used for this purpose.

5 The main object of my invention is to provide improved inexpensive means for conveniently and effectively metering the hot water fed to a boiler.

A further purpose is to use the catch basin 10 of a weir as a temperature-equalizing jacket for the inlet to the weir.

A further purpose is to locate a V-notch 15 weir within the drum of a boiler, discharging axially of the boiler, transversely to the axis, or at an angle to these as may be preferred 20 and using one or a number of weirs as suits the convenience.

A further purpose is to have the temperature 25 of the water flowing over the weir essentially that of the steam within the boiler, thus avoiding errors and disturbances from rapid condensation of the steam upon the surface of the water above the weir.

A further purpose is to accomplish this 30 equalization in temperature between the steam and the surface of the water above the weir by sending the incoming water through a considerable length of piping below the surface of the water within the boiler before discharging it into the weir box. Much the same advantage may be gained by extending the 35 weir chamber below the surface of the catch basin water in the boiler.

Further purposes will appear in the specification and in the claims.

In the drawings:—

Figure 1 is a broken sectional elevation of a boiler drum equipped with one form of my invention.

40 Figure 2 is a broken sectional elevation of a boiler drum equipped with the second form of my invention.

Figure 3 is a broken sectional elevation of a boiler drum equipped with my invention and 45 provided with weirs at each end.

Figure 4 is a broken side elevation similar to Figure 3 of a modification used to obtain better equalization between the temperature 50 of the water within the weir boxes and that of the steam within the boiler.

Figure 5 is an end elevation of Figures 3 and 4 and illustrates the recording mechanism.

Figure 6 is a top plan view of Figure 3.

Figure 7 is a section of Figure 3 upon line 55 7—7.

Figures 8 and 9, 10 and 11, and 12 and 13, are respectively transverse and longitudinal 60 sections of drums equipped with modified forms of my invention and show multiple weirs.

Figure 14 is a longitudinal section of still another modification.

In all the figures like numbers refer to like 65 parts.

Describing the invention in illustration and not in limitation and referring to the drawings:—

Within the boiler drum 15 I provide above 70 the surface of the water a weir box 16 having a baffle 17 dividing the weir box into an inlet chamber 18 and a weir chamber 19. At the end is a V-notch discharge weir 20. The water space of the boiler is used as the catch basin for the weir. The inlet chamber 18 75 of the weir box is provided with a float 21 which by means of the link connection 22 positions the crank 23, operatively connected to the pivot shaft 24. The shaft carries a lever having an operating arm 25 and a counterbalance arm 29 outside the boiler, one of them operating the mechanism of a recorder 26 by any suitable means, such as wire 27. The water level in the weir chamber and, therefore, by derivation from it, the flow of 80 water over the weir is shown at the recorder.

The bearing for the pivot shaft 24 carrying the crank 23 is suitably packed to prevent leakage and is preferably so placed as to maintain the greater part of the arm 23 always above the water level within the weir box, to avoid errors by reason of variation in buoyancy upon the arm supporting the float.

The float may be a cast iron disc or cylinder and is counterweighted by means of a weight 28 outside of the boiler and laterally adjustable on the arm 29, this arm 29 conveniently being an extension of the same arm 25 as is used to operate the recorder. 95 100

The counterweight is adjusted until the cast iron float is partially submerged in the water within the float chamber, and the float rises and falls with the water level within the 5 weir box, thus swinging the pivot shaft 24 and operating the mechanism of the recorder.

Counterbalance arm 29 carrying the counterweight is preferably coplanar with a connection 30 rigid with the crank arm 23 and 10 pivotally connected with the float, as this avoids any error from the change in the relative lengths of the arms of the float and its counterweight.

The feed water enters from a pipe 31 outside of the boiler through a pipe 32 within the boiler to the chamber 18 of the weir box under a baffle 33, the purpose of this baffle being to avoid undue currents within the chamber.

20 In Figure 1 the section of piping between the chamber 18 and the pipe 31 outside of the boiler is shown as merely making direct connection between the pipe 31 and the chamber 18. This form may be used whenever the 25 water entering the boiler has a temperature nearly that of the water already within the boiler, as by reason of having been preliminarily heated within a suitable economizer or other feed water heater to nearly the 30 temperature corresponding with the intended steam pressure.

It is not well to deliver water into the weir box unless it is nearly of temperature corresponding to the intended steam pressure, 35 both on account of the error resulting from the addition of condensed steam within the weir box, and if in large volume, on account of the fluctuation in pressure which would result within the boiler if a corresponding 40 fairly large surface of water of materially lower temperature than that corresponding to the steam pressure were exposed to the steam within the steam space of the boiler.

Cold water may be introduced with reasonable safety into a boiler well below the 45 surface of the water already there, the result of such introduction being to lower the average temperature of the water already in the boiler without any material tendency toward creating violent disturbances in the 50 water within the boiler, such as exists when water throughout a boiler partially and suddenly flashes to steam.

On the other hand it is unwise to introduce 55 relatively cold water directly into the steam space of the boiler as this may result in a sudden fall in steam pressure above the water in the boiler accompanied by flashing to steam throughout the water of the boiler 60 which may cause violent disturbance and even will risk actual rupture of the boiler.

In Figure 2, as in Figure 4, the length of the inlet pipe is artificially extended, either 65 by inserting it through the boiler casing at a considerable and unnecessary distance

from the weir chamber, or using a connection with the weir chamber as part of the inlet or by looping the inlet within the water space of the boiler in order to make sure that the temperature of the incoming water is approximately that of the water in the boiler. In Figure 2 I loop the inlet 32'.

In the form shown in Figure 3 there is a weir box at each end of the drum, the two boxes 16 and 16' respectively being connected 75 by means of piping 34 of sufficient size to maintain substantially the same level in both boxes.

Where the level and temperature conditions are the same within both boxes but a 80 single float and recording mechanism need be used, the V-notches of both boxes being adjusted to the same height. The inequality of the pipe lengths feeding the two weir chambers will make no difference when the feed 85 water at the start is of temperature substantially corresponding to that of the steam within the boiler.

Separate recorders may be used with any of the forms in which two weir boxes are 90 shown.

In the form shown in Figure 4 the form of Figure 3 is modified so that the water entering both of the weir boxes will have passed through the same length of piping 95 jacketed by water of the boiler thereby ensuring that the temperature of the water entering the weir boxes will in both boxes be substantially that of the water already in the boiler. The T 35 is preferably located half 100 way between the weir boxes 16 and 16' so that the length of hot water jacketed piping fed through the common inlet 32' shall be the same to both boxes.

One or both of the weir boxes are preferably 105 provided with water gauge glasses 36 and suitable scales 37 to permit the boiler operator to see roughly at a glance the rate of water delivery into the boiler, the rate of delivery being indicated by the position of the 110 water in the glass with reference to a zero on the scale.

The piping 32' to the weir box is provided with T's 38 and these T's and the openings of other piping as shown are closed by removable covers 39 giving easy access for cleaning purposes.

In the forms of Figures 8 and 9 the piping in which the feed water is preheated before entering the weir box and the inlet chamber 18 120 of the weir box of the preceding forms are replaced by a compartment 40 along one side of the drum.

It is advantageous to have within the weir box only a small water-surface exposure to the steam and to have the water at its exposed surface as near as may be to full steam temperature, to minimize condensation upon the water surface and pressure disturbances from such condensation. It is also advantageous 130

to have the conduit connection between the supply pipe 31 without the drum and the weir box 16 submerged by the water within the drum to prevent pressure fluctuations within the steam space by reason of any fluctuation of temperature of the feed water. Corresponding advantageous features are all possessed by the forms shown in these Figures 8, 9, 10 and 11. Both of these two forms have multiple notches (discharging in three directions in Figures 10 and 11) and locate the float chamber outside of the drum.

From a commercial standpoint it is desirable to increase the capacity of a weir by increasing the number of standard notches rather than by increasing the angular size of a single notch, as this dispenses with the need for a multiplicity of careful calibrations. And it is also desirable to have the float chamber a standard unit outside of the drum, in that the float is less affected by local waves and ripples and in that the manufacture and connections are adapted to exact standardization.

Because in Figures 8 and 9 one side of the compartment 40 is formed by the outer wall 41 of the drum, the compartment is not completely surrounded by the water of the drum, while in Figures 10 and 11 the compartment 40' comprises a tubular shell submerged and completely surrounded by the water of the drum. In both cases the weir chamber is an uptake 41 from an end of the compartment and in sectional area may be made as small as is consistent with non-interference with the normal relation between head and discharge over the weirs. Separate float chambers 42 are shown outside of the drum and are connected with the weir chambers by pipes 43 and 44, respectively above and below the surface of the water.

In Figures 12 and 13 the weir chamber is located near the middle of the drum and partially submerged.

Figure 14 shows the weir chamber extending the length of the drum and wholly above the water of the drum, an arrangement giving some of the advantages of my invention and particularly adapted for use when conditions are such that the feed water entering the drum is already as hot as the steam within the drum.

I recognize that my invention does not require a particular type or kind of recording connection and will be satisfied by any connections, mechanical or magnetic, by which the variations in the position of the float may be communicated to the recording devices outside of the boiler.

In view of my invention and disclosure modifications and variations will doubtless become evident to others skilled in the art by which all or a part of the advantage of my invention may be secured without copying the forms shown, and it is my intention to

include herein all such modifications and variations in so far as they fall within the reasonable spirit and scope of my invention.

Having thus described my invention, what I claim as new and desire to secure by Letters Patent is:—

1. The combination of a boiler, a weir box and weir in the steam space thereof, using the water space of the boiler as a catch basin, means including a float, connecting said weir box to a measuring device and a feed water inlet arranged to discharge into said weir box.

2. The combination of a boiler, a weir box and weir in the steam space thereof, using the water space of the boiler as a catch basin, means including a float, connecting said weir box to a measuring device, a feed water inlet arranged to discharge into said weir box and means within the boiler for substantially equalizing the temperature of the water entering the weir box with that already within the boiler.

3. The combination of a boiler, a weir box and weir in the steam space thereof, using the water space of the boiler as a catch basin, means including a float connecting said weir box to a measuring device and a feed water pipe supplying water to the weir box and having an artificially extended length lying beneath the water within the boiler.

4. The combination of a boiler, a weir box and weir in the steam space thereof, a float and connections for measurement of flow therein and a feed water pipe to the weir box departing from the shortest connection with the exterior of the box to have a considerable portion of its length jacketed by the water within the boiler.

5. The combination of a boiler, a weir box therein, a weir, a catch basin, a float and connections for measurement of water therein, and a feed water pipe to the weir box having an artificially extended length within the catch basin in order to substantially equalize the temperature of the water entering the weir box with that of the water already in the catch basin.

6. The combination of a boiler, a weir box near each end thereof, using the water space of the boiler as a catch basin, a weir in each box, means including a float, connecting one of the weir boxes with a measuring device, a conduit connection under the water of the boiler between the boxes discharging into the boxes, and a feed water connection to the conduit.

7. The combination of a boiler, a weir box near each end thereof, using the water space of the boiler as a catch basin, a weir in each box having a predetermined relation between the flows over the weirs, a float and connections for measurement of water flowing from one of the boxes, a conduit connection under the water of the boiler between the boxes and

a feed water connection to the conduit.

8. The combination of a boiler, a weir box near each end thereof, using the water space of the boiler as a catch basin, a weir in each box 5 having a predetermined relation between the flows over the weirs, a float and connections for measurement of water flowing from one

of the boxes, a conduit connection between the boxes and under the surface of the water of the boiler, and a feed water connection under the 10 surface of the water of the boiler into the conduit at approximately midway between the boxes.

HERMAN C. HEATON.
